UNITED STATES PATENT OFFICE

2,410,521

TAPE FEED ALARM

Louis M. Potts, Evanston, Ill., assignor to Teletype Corporation, Chicago, Ill., a corporation of Delaware

Application May 22, 1942, Serial No. 444,067

13 Claims. (Cl. 177—311)

1

This invention relates to telegraph transmitting apparatus and particularly to a strip feed alarm device for indicating the manifestation of defective strip feeding conditions.

In the telegraph communication field, tape is employed as a medium for carrying indicia of telegraph signal code combinations, usually in the form of permutably arranged perforations. Ordinarily, the tape is first perforated either by means of key operated perforator or by means of a signal controlled reperforator and later used in connection with a tape transmitter to send signals in code combination form over an outgoing line. The tape, in performing its operating functions, is subject to stresses and strains which may at times cause the tearing of the feed holes and possibly a complete rupture of the tape. It is apparent that any such undesirable conditions may seriously impair transmission of messages and cause distortion or loss of signals, particularly so if such conditions were not immediately rectified. The use of tape operated transmitters which are unattended by an operator is growing constantly and consequently the desirability of the arrangement as herein provided is enhanced inasmuch as the problem of defective tape feeding conditions is obviously not as serious when a transmitter is under the constant surveillance of an operator.

It is therefore the prime object of this invention to provide a mechanically controlled strip feed alarm which immediately brings to an operator's attention the manifestation of a defective tape feeding condition.

Other objects, features and advantages of the present invention will become evident as the invention is further described in detail.

By the present invention there is provided a mechanically controlled alarm device in which two contact operating levers are normally maintained in inoperative positions by a cam arrangement and wherein a relative displacement of the cams included in the arrangement when defective tape feeding conditions occur, causes one or the other of the levers to operate both an audible and a visible signaling means. The use of both audible and visible signal indicating means in the present invention is particularly desirable in view of the fact that the apparatus herein disclosed is designed especially for use in installations which may include a large number of transmitters. It is therefore necessary to bring to the operator's attention not only an indication of the occurrence of a defective feeding condition by an audible signal but also by a visible signal as well in

2

order that the operator may know in which particular one of the transmitters the condition exists.

The invention will be more readily understood by reference to the following detailed description and the drawing wherein,

Fig. 1 is a perspective view of one embodiment of the present invention partly in section and with certain portions of the apparatus omitted for the sake of clarity;

Fig. 2 is a plan view of the embodiment of the invention disclosed in Fig. 1;

Fig. 3 is a schematic representation of the cams used in connection with the invention disclosed in Figs. 1 and 2;

Fig. 4 is a plan view partly in section of a second embodiment of the present invention;

Fig. 5 is a side view partly in section of the apparatus disclosed in Fig. 4; and

Fig. 6 is a perspective view of the cam control means employed in the embodiment of the invention disclosed in Figs. 3 and 4.

Referring now to the drawing, the first embodiment of the invention which is disclosed in Figs. 1, 2, and 3 will now be described in detail. The present invention may be conveniently incorporated for use with tape transmitters such as disclosed in the patent to M. T. Goetz, Patent No. 2,296,845 issued September 29, 1942, and in order to facilitate the description of the present application it will be presumed that the ratchet wheel 56 disclosed therein, the shaft 58 which carries the ratchet 56, and the sprocket wheel 59 are the same as the similarly numbered elements appearing in the present disclosure. As

described in detail in the just referred to patent, the tape is intermittently fed forward as the ratchet 56 is periodically advanced by means of a pawl associated with a stepping magnet which thereby causes the rotation of the shaft 58 and the tape feed sprocket 59. In the present invention there is attached to the shaft 58 by means of a set screw 60 a sleeve 61 which fixedly carries a pair of cam members 62 and 63 which are thus mounted for rotation with the shaft 58.

To the rear of the feed sprocket 59 directly in alignment therewith is provided a second feed sprocket 65 which is freely rotatable about a shaft 66 which is suitably mounted in the transmitting apparatus. The sprocket 65 is attached to the sleeve 67 and rotatable therewith about the shaft 66. Carried at the end of the sleeve 67 opposite the sprocket 65 is a pair of cams 68 and 69 which are similar in configuration to the cams 62 and

63 which were previously described.

Referring now again to the shaft 58 (Fig. 2) it can be seen that there is carried thereon for rotation therewith a gear 71 which drives an idler gear 72 which in turn drives a gear 64 which is fixedly attached to the shaft 66. It is therefore apparent at this point that as the sprocket feed wheel 59 intermittently advances the tape 110 forward, the pull of the tape enables the second sprocket wheel 65 to be also intermittently advanced inasmuch as the feed holes of the tape are positioned on the pin projections of both sprockets. It is therefore further observable that inasmuch as sleeve 67 is attached to sprocket 65, as sprocket 65 is advanced, the sleeve 67 will also be advanced and will carry the cams 68 and 69 with it during its advancing operations. At the same time it will be noted that the pair of cams 62 and 63 which are carried by the sleeve 61 mounted on shaft 58 will likewise be intermittently advanced so that a phase relationship will be normally maintained between the two sets of cams. It will be understood that the gear arrangement will be such that sprockets 59 and 65 will be intermittently rotated the same relative distances during normal operation of the apparatus.

Mounted in alignment with cam 63 associated with shaft 58 and cam 69 associated with shaft 66 is a contact operating lever 73 which has an upstanding arm 74 adapted to cooperate with the cam 69 and a second upstanding arm 75 adapted to cooperate with the cam 63. A horizontally extending arm 76 of the lever 73 is in engagement with an insulating portion 77 of a contact spring 78 which is normally spring urged away from its associated spring contact member 79. The lever 73 is normally urged to rotate in a counterclockwise direction about pivot shaft 82 as viewed in Fig. 1 under the influence of spring 81 so that the upstanding projection 75 and the upstanding projection 74 are urged into engagement with their associated cams. Also mounted upon the shaft 82 is a second lever 83 which is exactly the same in construction as the just described lever 73. Upstanding portion 84 of lever 83 is adapted to cooperate with cam 68 while the upstanding arm 85 of lever 83 is adapted to cooperate with the cam 62 and the horizontally extending arm 86 is adapted to cooperate with the insulating portion 77 of contact spring 78 in a similar manner to the horizontally extending arm 76 of lever 73 and likewise a spring 87 normally urges lever 83 in a counterclockwise direction as viewed in Fig. 1. The contact spring 78 is therefore common to and operable by either lever 73 or 83.

The raised portions of cams 62 and 63 will be slightly in excess of 90 degrees of their respective peripheral contours (Fig. 3) while the recessed portions of the cams will be slightly less than 90 degrees of their respective peripheral contours and the cams 62 and 63 will be so positioned with relation to each other that the high portions of one cam will be opposite the low portion of the other cam as shown in Fig. 1, for a purpose which will hereafter appear. The high portions of cams 68 and 69 will consist of segments of slightly less than 90 degrees of the peripheral contour of the cams while the recessed portions of these cams will be slightly in excess of 90 degrees of the peripheral contour of the cams and the raised portions of cam 68 will be positioned adjacent the recessed portions of cam 69 as clearly shown in Fig. 1.

It can now be seen by referring to Fig. 1 that

as long as the tape 110 is being fed forwardly by sprocket 59 and the sprocket 65 is being rotated through the intermittent pull of the tape 110, the levers 73 and 83 will be retained in a clockwise position. This is due to the fact (referring first to lever 73) that cams 62 and 63 when in phase relationship with cams 68 and 69 are so arranged that the high portions of the cams work alternately against the upstanding arms 75 and 74. Cams 63 and 69 are normally so positioned that when the end of arm 75 has been traversed by a high portion of the cam 63 the other arm 74 will have already been engaged by the high portion of cam 69. Lever 84 is controlled in a similar manner by its associated cams and it is therefore apparent that as long as operating conditions are normal, neither one of the levers 73 or 83 will be allowed to pivot and close the contacts 91 to cause operation of an alarm device to be hereafter described. Should a breakage of tape occur, shaft 58 will continue to rotate and drive the cams 62 and 63 while the sprocket 65 will no longer rotate inasmuch as the tape no longer exerts a pull thereon, and therefore cams 68 and 69 come to a stop. At this time either one or the other of the arms 74 of lever 73 or the arm 84 of the lever 83 rests on a high portion of the cam while the other arm is positioned over a low portion of the cam. Therefore, if for instance arm 74 of lever 73 were over a low portion of cam 69 when shaft 66 came to a halt then when cam 63 is in a position whereat the arm 75 may engage a recessed portion of its cam, the lever 73 would be able to pivot to a position under the influence of spring 81 to close the contacts 91 and operate the alarm device. Of course, a similar condition would occur if the arm 84 of lever 83 came to a position overlying a recessed portion of cam 68 when the shaft 66 came to a stop.

The pair of cams 68 and 69 are provided with raised portions slightly less than 90 degrees and with recessed portions slightly more than 90 degrees with the high portions of one cam adjacent the low portions of the other cam. This enables an overlapping cooperation of the high portions of cams 68 and 69 with the high portions of cams 62 and 63, respectively, which, as already mentioned, are slightly in excess of 90 degrees to normally hold levers 73 and 83 in their respective inoperative positions when operating in proper phase relationship. Due to the fact that cams 68 and 69 are staggered with respect to each other, that is, with the slightly under 90 degree high portions of one cam adjacent the slightly more than 90 degree low portions of the other cam, it is always assured that the cam engaging portion of one of the levers 73, 83 will overlie a low portion of one of the cams 68, 69 when they cease to rotate as explained, and is thus enabled to pivot and operate the alarm device irrespective of the stop positions of cams 68 and 69.

The closing of the contact pair 91 completes the alarm circuit over conductors 92 and 93 so that an audible signal 94 and the visible signal 95 are placed into operation and will be periodically operated thereafter as the shaft 58 continues to rotate to cause a periodic movement of the particular lever whose upstanding arm 74 or 84 was opposite a low portion of the cam when the shaft 66 came to a stop. The attendant at this time will thus be informed that a defective tape feeding condition has occurred and will then immediately be able to rectify the condition.

In order to reset the cams 68 and 69 into phase relationship with the cams 62 and 63, a special reset mechanism is provided which will now be described. In tape transmitters such as disclosed in the Goetz patent, already referred to, there is provided a bar 108 which is similar to the bar 108 disclosed in Figs. 1 and 2 and which is employed at the start of transmission to condition the apparatus for operation. Adjacent to the bar 108 is suitably mounted a bracket 109 which carries a U-shaped lever 111 which is pivoted at 112 and carries an extending arm 113. Lever 111 is normally urged in a counterclockwise direction by spring 120 as viewed in Fig. 2. The upper and lower arms 118 of the U-shaped member terminate in a rounded portion 115 which rides in a groove of a collar member 116 which is suitably keyed to a slot 117 in shaft 66 and rotatable therewith. The collar member 116 includes a pair of disc like side members 121 and 122. The disc member 122 has struck up therefrom an upstanding projection 123 adapted to cooperate with two pins 124 and 125 carried by sprocket 65 in a manner to be immediately hereafter described.

The U-shaped member 111 which is mounted upon bracket 109 is during normal transmission restrained from movement by the abutment of projection 113 with an extending portion 114 of the bar 108. However, when it is desired to start transmission or to reset the tape sprockets into phased relationship, the bar 108 is depressed and the projecting portion 114 of the bar is removed from the path of the projection 113 so that the U-shaped member 111 is then free to move in a counterclockwise direction as viewed in Fig. 2 under the influence of spring 120. This causes the upper and lower arms 118 of the U-shaped member 111 to shift the collar member 116 axially upon the shaft 66 along the keyway 117 to its phasing position.

When inserting a new or an unused portion of a broken tape, the operator depresses the bar 108 with one hand and with the other hand positions the tape upon the sprocket 65 and thereafter with the same hand rotates the sprocket 65 manually until sufficient tape has been fed out for engagement with the main feeding sprocket 59. The sprockets 65 and 59 will be so placed with respect to each other that by the time the tape has been positioned upon the front sprocket one or the other of the pins 124 or 125 will have come into engagement with the upstanding projection 123 of disc member 122 of collar member 116 which is carried by the shaft 66 and therefore the sprocket will again be returned to a phase relationship. This occurs when the collar member 116 assumes its phasing position as described above. Due to the fact that the collar 116 is rotatable with the shaft 66, as the sprocket 65 is rotated manually by the operator, a point will be reached as explained wherein the pins 125 or 124 will engage with the projection 123 so that the sprocket 65 and the collar 116 will thereafter rotate as a unit and thereby the gear members 64, 71, and 72 will be likewise rotated to therefore set in motion the sprocket 59. It can thus be seen that by means of this mechanism the sprockets may be readily returned to their exact phase relationship which they will continue to maintain until the tape again breaks or for some other reason fails to advance the tape.

Referring now to Figs. 4, 5, and 6, the second embodiment of the invention herein disclosed will

now be described. This second embodiment of the invention may also be readily incorporated into the previously referred to transmitter disclosed in the Goetz patent. It will be presumed that ratchet wheel 156 is equivalent to the ratchet wheel 56 shown in Figs. 1 and 2 and likewise the shaft 158 and feed sprocket 159 are equivalent to shaft 58 and the feed sprocket 59, respectively, as disclosed also in Fig. 1. It had been previously mentioned that the parts 56, 58, and 59 of Figs. 1 and 2 were numbered similarly to the like parts appearing in the Goetz patent. Shaft 158 will be suitably journaled in the frame and will be intermittently advanced by the engagement of a stepping pawl with the ratchet 156 as is well known in the art. The tape 161 will be threaded over the teeth of the feed sprocket 159 and will be therefore intermittently advanced as the ratchet 156 is actuated. Carried at the end of the shaft 158 opposite to the ratchet 156 is a gear 162 which drives a suitably mounted idler gear 163 which in turn causes the rotation of a driving gear 164. In mesh with the driving gear 164 is a second idler gear 165 which drives the gear 166. Integrally formed with the gear member 164 is a sleeve 167 which carries a cam member 168 having a peripheral contour in which the raised portion of the cam is slightly in excess of 180 degrees. The sleeve 167 is attached to the shaft 169 by means of a set screw 171 and it is thus obvious that the shaft 169 is rotatable with the gear 164.

Also mounted upon the shaft 169 and freely rotatable thereon is a second feeding sprocket 172 which is directly in alignment with the first feeding sprocket 159. It is therefore observable that as the tape 161 is advanced by the first feeding sprocket 159 inasmuch as the tape by means of its feed holes engages the teeth of the second feeding sprocket 172, the second feeding sprocket 172 will be rotated about the shaft 169 by the pull of the tape. The feed sprocket 172 has integrally formed therewith a sleeve 173 which surrounds the shaft 169 and carries a cam member 174 which has a peripheral contour in which the raised portion of the cam is slightly less than 180 degrees for a purpose which will hereinafter appear.

When the tape is properly advanced by the feeding mechanism, the cams 174 and 168 will be so arranged that their high portions together present a 360 degree closed surface to the cam engaging portions 176 of a pair of levers 177 and 178 which are pivoted at 179 and 181, respectively, and the same engaging portions 176 of which are 180 degrees apart and normally urged towards each other by means of resilient spring members 180 associated with contacts 183 and 184. The lower end portions of the levers 177 and 178 terminate in curved contact engaging portions 119. These contact engaging portions 119 are adaptable to cooperate with contact members 183 and 184 which control the alarm circuit. Normally the contact engaging portions 119 of the levers rest against the insulating members 185 associated with the resilient spring members 180 of the contacts and hold the spring members in flexed condition to thus urge the levers 177 and 178 to pivot towards each other. However, should a defective or irregular tape feeding condition occur one or the other of the levers will be pivoted under the influence of the spring contact members 180 as will later appear and will close one or the other of the contact members 183, 184. The closure of either of the contacts enables one of the parallel circuits 186 and 187

to become effective to operate an audible alarm device 188 and the other to operate a signal lamp 189 which will announce to the operator the occurrence of a defective tape feeding condition.

The operation of the contact control levers 177 and 178 will now be described in more detail. It will be presumed that the tape stepping sprocket 159 is in normal operation and is intermittently advancing the tape 161. If a breakage of the tape should now occur, the main tape feed sprocket 159 will continue to operate. However, due to the fact that the second tape feed sprocket 172 is operated by the pull of the tape it will come to rest. Therefore, inasmuch as the cam 174 is carried by the sleeve 173 which is connected to the feed sprocket 172, this cam will likewise come to rest. On the other hand, the cam 168 will continue to rotate by means of the drive afforded by the gears 162, 163, and 164. In view of the fact that the high portion of the cam 174 is slightly less than 180 degrees and the cam engaging portions 176 of the levers 177 and 178 are 180 degrees apart, one of the levers will be held in its outer position by engagement with the high portion of cam 174. When the cam comes to rest, while the other lever will be opposite the low portion of the cam and when the cam 168 is in a position to also present its low portion to this last mentioned lever, the lever will be permitted to carry its cam engaging portion 176 inwardly under the influence of its associated spring contact member 180, enabling its contact engaging portion 119 to operate its associated contact member 183. The alarm device will then thereafter be intermittently operated as the cam 168 continues to rotate and present its low portion to the lever whose cam engaging portion 176 happens to be opposite the low portion of the cam 174. This condition will continue until the operator has made the necessary corrections in the apparatus.

It will be understood that a similar resetting mechanism which was described in connection with Figs. 1 and 2 could be readily incorporated into the embodiment of the invention disclosed in Figs. 4, 5, and 6 by mounting a collar member such as 116 disclosed in Fig. 2 upon the shaft 169 and providing the other necessary equipment which has already been described.

The purpose of providing the additional idler gear 165 and the additional driven gear 166 in mesh therewith is to enable the rotation of a suitably journaled shaft 192 which carries a third feeding sprocket 193. As shown in the drawing, the third feeding sprocket 193 is in direct alignment with the feeding sprockets 159 and 172 but is in a slightly elevated position with respect thereto. The purpose of this arrangement is to enable a considerable portion of the tape to move over the periphery of the feed sprocket 193 to thereby enable a better distribution of strain upon the tape. A strain relieving sprocket is particularly desirable in cases where the tape may be fed from a relatively large supply reel and in cases wherein it makes for better operation of the tape transmitter to remove the strain from the tape prior to the movement of the tape into the transmitter proper where it performs its transmitting operations. One particular advantage of this is that it enables the centralization of the feed holes of the tape upon the teeth of the sprocket wheel thus assuring the correct alignment of the signal perforations of the tape with the sensing mechanism commonly employed in tape transmitters. If a strain were placed upon the tape at the main feeding sprocket, the feed

holes would not be centralized with respect to the teeth of the sprocket but would be pulled to one side by the teeth of the sprocket. This would cause a slight misalignment of the signal perforations with the tape feelers and might impair the efficiency of signal transmission.

It will be understood that various changes and modifications may be made in the above-described specification without departing from the spirit and scope thereof.

What is claimed is:

1. In a tape feed alarm, feeding means for advancing a strip, a cam mechanism, means for operating said cam mechanism under the joint control of said strip and said feeding means, an alarm device, a pair of levers controlled by said cam mechanism for operating said alarm device, and means included in said cam mechanism for enabling the operation of one of said levers upon the failure of said strip to exercise control of said cam mechanism to thereby enable actuation of said alarm device which of said levers being actuatable depending on the phase positioning of said cam mechanism.

2. In a strip feed alarm, feeding means for advancing a strip, a first pair of movable cam members, means for moving said first pair of cam members in synchronism with the movement of the strip feeding means, a second pair of movable cam members, means for moving said second pair of cam members in synchronism with the movement of said strip to maintain a phase relationship with said first pair of cam members, and an alarm device controlled by said pairs of cam members, whereby said alarm device is operated by said pairs of cam members when said strip fails to maintain said phase relationship between said pairs of cam members.

3. In a strip feed alarm, feeding means for advancing a strip, a first pair of movable cams, means for moving said first pair of cams in synchronism with the movement of the strip feeding means, a second pair of movable cams, means for moving said second pair of cams in phase with said first pair of cams and in synchronism with the movement of said strip, a pair of levers each controlled by a cam of each pair of cams, and an alarm device operable by either of said levers, whereby one or the other of said levers is actuatable to operate said alarm device when said pairs of cams are not maintained in phase by said strip, which of said levers being actuatable depending on the phase positioning of said cams.

4. In a strip feed alarm, feeding means for advancing a strip, a first pair of movable cams, a second pair of movable cams, said first pair of cams moving in synchronism with the movement of the strip feeding means and said second pair of cams moving in phase with said first pair of cams and in synchronism with the movement of said strip, an alarm device, and a pair of levers to control said alarm device, each of said levers being alternately controlled by a single cam of each pair of cams, whereby one or the other of said levers is actuatable to operate said alarm device upon the failure of said strip to maintain said phase condition of said cams, which of said levers being actuatable depending on the phase positioning of said cams.

5. In a strip feed alarm, feeding means for advancing a strip, a first movable cam, means for moving said first cam in synchronism with the movement of the strip feeding means, a raised portion on said cam, a second movable cam, means for moving said second cam in phase with

the first cam and in synchronism with the movement of said strip, a raised portion on said second cam, an alarm device, and a pair of levers each having a portion engaging with said cams, whereby said raised portions of said cams are normally positioned with respect to each other to present a closed peripheral surface to said cam engaging portions of said levers while said phase condition is maintained to normally prevent operation of said levers, whereby one or the other of said levers is operative to control said alarm device upon the failure of said strip to maintain said closed peripheral surface of said cams under said phase conditions, which of said levers being actuatable depending on the phase positioning of said cams.

6. In a tape feed alarm, feeding means for advancing a tape, a shaft for driving said feeding means, a cam member carried by said shaft, a second shaft, a second cam member carried by said second shaft moving in synchronism with said tape to maintain a phase relationship with said first cam member, and an alarm device controlled by said cam members, whereby said alarm device is operable under the control of said cam members upon the failure of the maintenance of said phase relationship between said cam members.

7. In a strip feed alarm, feeding means for advancing a strip, a shaft, a pair of movable cams carried by said shaft and operated by said feeding means, a second shaft, a second pair of movable cams carried by said second shaft and moved in phase with said first pair of cams in synchronism with the movement of said strip, a pair of levers each controlled by a cam of each pair of cams, and an alarm device operable by either of said levers, whereby one or the other of said levers is actuatable to operate said alarm device when said pairs of cams are not maintained in phase by said strip, which of said levers being actuatable depending on the phase position of said cams.

8. In a tape feed alarm, feeding means for advancing a tape, first movable cam means, means for moving said first cam means in synchronism with the movement of said tape feeding means, a second movable cam means, means for moving said second cam means in synchronism with the movement of said tape to maintain a predetermined relationship with said first cam means, an alarm device including electrical contact means, and a pair of levers each engaging both of said cam means whereby when said phase relationship fails between said first and second cam means one of said levers closes said electrical contact means to cause said alarm device to operate, which of said levers being actuatable depending on the phase positioning of said cam means.

9. In a tape feed alarm, feeding means for advancing a tape, a first movable cam means, means for moving said first cam means in synchronism with the movement of said feeding means, a second movable cam means, means for moving said second cam means in synchronism with the movement of said tape to maintain a predetermined phase relationship with said first cam means, an alarm device including electrical contact means, and a pair of levers jointly controlled by both of said cam means, whereby when said phase relationship fails between said cam means one of said levers closes said electrical contact means to cause said alarm device to operate, which of said levers being actuatable

depending on the phase positioning of said cam means.

10. In a tape feed alarm, feed means for advancing a tape, a first movable cam means, means for moving said first cam means in synchronism with the movement of said tape feed means, a second movable cam means, means for moving said second cam means in synchronism with the movement of said tape and in phase with the operation of said first cam means, each said first and second cam means provided with complementally related peripheral contours, lever means in contact with both said cam means, and an alarm means controlled by said lever means which is ineffective when the complemental peripheries of said cam means are in phase and effective when the complemental peripheries of said cam means are out of phase.

11. In a tape feed alarm, feed means for advancing a tape, a first movable cam means, means for moving said first cam means in synchronism with the movement of said tape feed means, a second movable cam means, means for moving said second cam means in synchronism with the movement of said tape and in phase with the operation of said first cam means, each said first and second cam means comprising a pair of cams, corresponding ones of which are provided with complementally related peripheral contours, and an alarm means ineffective when the complemental peripheries of said corresponding cams are in phase and effective when the complemental peripheries of said corresponding cams are out of phase.

12. In a tape feed alarm, feed means for advancing a tape, a first movable cam means, means for moving said first cam means in synchronism with the movement of said tape feed means, a second movable cam means, means for moving said second cam means in synchronism with the movement of said tape and in phase with the operation of said first cam means, each said first and second cam means provided with complementally related peripheral contours, a pair of levers each jointly controlled by said first and second cam means, and an alarm means operable by either of said levers, whereby one or the other of said levers is actuatable to operate said alarm means when the complemental peripheries of said cam means are out of phase, which of said levers being actuatable depending on the phase positioning of said cam means.

13. In a tape feed alarm, feed means for advancing a tape, a first movable cam means, means for moving said first cam means in synchronism with the movement of said tape feed means, a second movable cam means, means for moving said second cam means in synchronism with the movement of said tape and in phase with the operation of said first cam means, each said first and second cam means comprising a pair of cams, corresponding ones of which are provided with complementally related peripheral contours, a pair of levers each jointly controlled by one of said pair of cams of each of said first and second cam means, and an alarm means operable by either of said levers, whereby one or the other of said levers is actuatable to operate said alarm means when the complemental peripheries of said corresponding cams are out of phase, which of said levers being actuatable depending on the phase positioning of said cam means.
